HIRAM BEADLE, OF WASHINGTON, DISTRICT OF COLUMBIA.

Letters Patent No. 62,996, dated March 19, 1867.

IMPROVEMENT IN AUTOMATIC BOILER-FEEDERS.

The Schedule referred to in these Letters Patent and making part of the same.

TO ALL WHOM IT MAY CONCERN:

Be it known that I, HIRAM BEADLE, of Washington, in the District of Columbia, have invented a new and improved Automatic Water-Feeder for Steam Generators; and I do hereby declare that the following is a full, clear, and exact description of the same, reference being had to the annexed drawings, making part of this specification, in which—

Figure 1 is an elevation, with parts represented as broken away.

Figure 2 is a vertical section of the induction valve.

The following description will enable one learned in the art to make and apply my automatic water-feeder.

A is a water and steam chamber, into which the water flows from a reservoir through the pipe B, in which is placed a valve, C, opening inwards. D is a condensing-chamber communicating with the supply pipe B, and with the upper part of the supply-chamber. A screw, D¹, is placed in the bottom of the condensing-chamber. E is a float which may be of wood, but preferably a hollow metallic drum should be used as a float. This float rises and falls with the level of the water in the supply-chamber. The piston-rod F is attached to this float, passing through suitable stuffing-boxes in the ends of the chamber A. The collar F¹ is fastened upon this rod above the chamber. G is a sliding yoke, through eyes in which the guides H pass, permitting a free vertical play to the yoke. The yoke is connected with the stems of the valves K and K¹ by wires or rods I. The supply-chamber A is connected with the steam generator by the pipe L, which is so arranged that the bottom of the chamber shall be on the level of the low-water line of the generator. An outwardly-opening valve is placed in the pipe L, at M, which permits the water to flow from the supply-chamber A into the generator. The pipe N leads from the steam-chamber of the generator to the upper part of the supply-chamber; it is closed by a stop-cock. The valve K, when opened, allows the steam, to flow from the generator into the supply-chamber A; and the valve K¹, when opened, allows the steam to pass from the receiving-chamber into the condenser D, and the water to pass from the condenser into the chamber A.

The operation of this automatic feeder is as follows: Supposing the boiler to be filled with water, and the steam to be raised to a proper pressure in the generator, the engineer raises the rod F and float E; the pipe B being opened, the water will flow into and fill the chamber A. The collar F¹ will raise the yoke G, and open the steam pipe K, closing at the same time the valve K¹. The pipe N being opened by turning the steam-cock, the water in the supply-chamber A will be subjected to the same pressure as that in the boiler, and the valve C will be supplied by that flowing closed by the pressure. As the water falls by evaporation in the boiler, it will be supplied by that flowing into the generator from the supply-chamber through the pipe L, which opens below the surface of water in the generator. When the water falls in the generator so as to draw all the water from the supply-chamber, the float E and rod F falling with it, the collar F¹, striking upon the levers of the valve K and K¹, will bear them down, closing the communication with the steam-chamber of the generator, and opening that with the condenser. The steam which fills the supply-chamber will be immediately condensed, and the water flow in through the supply pipe B, filling the chamber A and raising the float E and rod F, until the collar F¹ raises the yoke G and closes the valve K¹, and opens the valve K, when the operation already described is repeated. A stop-cock is placed on the end of the supply-chamber A. Through this the air will be permitted to escape on the entrance of the water in starting the apparatus. Where the reservoir is not above the supply-chamber, the steam must be admitted to the supply-chamber in starting; in order to commence the action of the apparatus, the rod F being raised by hand. When the cylinder A is filled with steam, the rod is pressed down so as to close the steam valve K and open the valve K¹, and the automatic action of the apparatus will be thereafter continued.

What I claim as my invention, and desire to secure by Letters Patent, is—

1. The arrangement of the pipe B, condenser D, valve C, pipes I and N, with reference to the chamber A and float E, substantially as herein set forth.
2. The combination of the supply pipe B, valve C, and chamber A, with the float E, rod F, and valves K and K¹, substantially as and for the purpose set forth.
3. The combination of the rod F, yoke G, rods I, and valves K and K¹, substantially as and for the purpose set forth.

In testimony whereof I have signed my name to this specification in the presence of two subscribing witnesses.

HIRAM BEADLE.
